UNITED STATES PATENT OFFICE

136,697

DESIGN FOR A PIPE COUPLING CLAMP OR THE LIKE

Eugene Pitou, New York, N. Y., assignor to The Patent Scaffolding Company, Long Island City,
N. Y., a corporation of New York

Application April 22, 1942, Serial No. 106,659

Term of patent 14 years

To all whom it may concern:

Be it known that I, Eugene Pitou, a citizen of the United States, residing at 1010 Fifth Avenue, in the city, county, and State of New York, have invented a new, original, and ornamental Design for a Pipe Coupling Clamp or the like, of which the following is a specification, reference being had to the accompanying drawing, forming part thereof.

Fig. 1 is a perspective view of a pipe coupling clamp or the like showing my new design;

Fig. 2 is a top plan view thereof;
Fig. 3 is a side elevational view thereof;
Fig. 4 is an elevational view of one end; and
Fig. 5 is an elevational view of the opposite end thereof.

I claim:

The ornamental design for a pipe coupling clamp or the like, as shown.

EUGENE PITOU.
